BENJAMIN ROBERTS, OF LAKE SASKATOON, ALBERTA, CANADA.

SAW SET AND GAGE.

1,356,221.

Specification of Letters Patent. Patented Oct. 19, 1920.

Application filed April 25, 1919. Serial No. 292,689.

To all whom it may concern:

Be it known that I, BENJAMIN ROBERTS, a subject of the King of Great Britain, residing at Lake Saskatoon, in the Province 5 of Alberta, Dominion of Canada, have invented certain new and useful Improvements in Saw Sets and Gages, of which the following is a specification.

This invention relates generally to tools, 10 and particularly to instruments adapted to be used in the repair or setting of saws, aiming primarily to provide a combined saw-set and gage, improved means for holding a file to operate upon the saw teeth in the adjusting or trying of the latter, improved means for gaging raker teeth, as well as the embodiment of other elements 15 for performing different functions.

A further object of the invention is to 20 provide a tool of this character wherein a pair of pivoted handle or jaw members are employed, the said handle members being provided with coöperating serrated faces to effect a pipe or nut gripping instrument, and means on one of the handles whereby bolt threads may be cleaned or 25 trued.

A still further object of the invention is to 30 provide a tool or implement of this character, which is simple in construction, which is inexpensive in manufacture, which is composed of few readily assembled parts, the said parts being so arranged and connected as to provide a powerful instrument 35 and one which will not readily become broken or damaged and which will prove thoroughly efficient in performing the functions for which it is designed.

With these objects in view, together with 40 others which will appear as the description proceeds, the invention resides in the novel formation, combination and arrangement of parts, all as will be described more fully hereinafter, illustrated in the drawings, and 45 particularly pointed out in the claims.

The invention will be best understood by reference to the accompanying drawings, 50 therein:

Figure 1 is an end view of a tool constructed and arranged in accordance with 55 my invention;

Fig. 2 is a side elevation of the tool and

illustrating the same when used as a saw set;

Fig. 3 is an end view of the tool opposite 55 to that shown in Fig. 1; and

Fig. 4 is a sectional view taken upon line 4—4 of Fig. 2.

Referring more particularly to the drawings, 5 and 6 represent a handle or jaw portions employed in carrying the invention into effect. The handle portion 5 is formed at one end to provide an angular portion 7, the latter being bifurcated as shown, and the space between the furcations extending 60 inwardly from the adjacent handle end. The opposite or coöperating handle member 6 is provided at one extremity with a disk or hammer portion 8, the latter being pivoted eccentrically as at 9 between the furcations of the angularly extending portion 7 of the handle 5. This hammer 8 is of substantially the same thickness at its point of pivotal connection with the member 5 as the distance between the furcations thereof, 65 while its sides taper toward the outer annular edge so that the thickness of the hammer is materially reduced. The handle 6, when swung inwardly will rock upon the pivot 9 and the hammer 8 will move inwardly into close proximity to the straight 70 portion of the handle member 5.

An anvil 10 is extended through the slotted or bifurcated end of the handle portion 5, and consists of a set screw which is 85 provided with locking nuts 11 to maintain the said set screw in adjusted position within the said slotted end. The inner extremity of the anvil is adapted to impinge a saw blade during the setting operation of 90 the tool to hold the latter while the hammer 8 operates to properly incline or set the teeth thereof. A gage screw 12 extends through a suitable opening formed in the handle 6 substantially intermediate the ends 95 of the latter. This gage screw is also provided with locking nuts 13, the arrangement enabling the gage screw to be readily adjusted through the said handle in a manner similar to that of the anvil 10. The gage 100 screw 12 is adapted to be adjusted in such a manner as to bear against the outer or metal portion of the saw blade when the tool is adjusted to the saw to position the

tool properly prior to the setting operation of the same.

By inclining the side faces of the disk portion 8 to present a relatively narrow 5 outer edge, it is apparent that the device is capable of being readily used upon saws having teeth varying in width.

The inner face of the handle member 6 is notched at 14 adjacent the juncture of the 10 hammer 8 with the handle member. This notch provides angular walls, the latter being spaced apart a distance sufficient to accommodate the edge of the ordinary flat file. When a file is placed within the grooves and 15 the handles 5 and 6 swung together, the said file will be firmly maintained in proper position to be passed over the teeth of a saw to properly aline the cutting ends or apices thereof. The file may, with facility, be removed 20 when required but during the filing operation, the said file will be firmly held in proper position.

In order that the tool may be efficiently used with various types of saws, the handle 25 6 is bent at one edge to provide a longitudinally disposed channel or groove 15, the said groove being of a width sufficient to accommodate relatively heavy saws. This groove extends throughout substantially one 30 half the length of the handle portion 6 and the said handle is cut away at its turned edge to provide a slot 16 communicating with the interior of the channel 15. In truing and sharpening saws of the raker type, 35 the handle 6 of the tool is positioned over the saw teeth with the raker teeth projecting through the slot 16. As the cutting teeth upon each side of the raker tooth engage with the bottom of the channel 15, the 40 said raker tooth will be alined with the slot, and will intrude through the same such distance as the same is out of cutting alinement with the cutting teeth of the saw. It is thus seen that an effective gage for evening 45 the raker teeth is provided. The extremity of the handle member 6 may be pointed or flattened as at 17 to provide a screw driver.

The opposite handle 5 has arranged therein, a plurality of internally threaded openings 18, the latter varying in diameter, and are adapted to be used to clean and even the threads or screw bolts by rotating the latter in said openings.

The free extremity of the handle member 5 is crotched to provide a tack lifter or 55 puller 19.

To enable the tool to be used as a pipe or nut wrench, the adjacent faces of the handle members 5 and 6 are serrated as shown and provide gripping teeth 20, the latter being 60 relatively sharp to insure a firm grip upon the material with which the device is used.

It is obvious from this description that I have provided a tool which is of extremely simple inexpensive construction, and which 65 may be efficiently used in the performing of a number of functions. The readiness with which the various parts of the device may be adjusted enables the tool to be readily adapted to its various uses. 70

While the above is a description of the preferred embodiment of the invention, it is apparent that various changes in the minor details of construction and arrangement of parts may be resorted to without departing from the spirit of the invention or exceeding the scope of the claims. 75

What is claimed is:—

1. A saw set and gage including two handles one of which has its working end 80 turned at right angles and slotted, a screw arranged through said handle and projecting beyond the walls thereof to provide an anvil, the opposite handle having its working end flattened and eccentrically pivoted 85 in the slotted end of the opposite handle to capacitate as a hammer to impinge the saw teeth and force them against the anvil.

2. A saw set and gage including a pair of handles one of which has its working end 90 turned at right angles, a screw arranged through said handle and projecting beyond the walls thereof to provide an anvil, the opposite handle having its working end flattened and eccentrically pivoted in the right 95 angle portion of the opposite handle to capacitate as a hammer for coaction with the anvil, and a screw arranged immediately in one of the handles to impinge the saw blade and operate as a gage. 100

In testimony whereof I affix my signature in presence of two witnesses.

BENJAMIN ROBERTS.
